CLAIM

The ornamental design for a record player, as shown and described.

DESCRIPTION

FIG. 1 is a top, front, right side perspective view of a record player showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" framed in FIG. 1; and,

FIG. 10 is an enlarged view of the portion labeled "10" framed in FIG. 10.

The broken lines show features of the record player that form no part of the claimed design. In FIG. 1, FIG. 9 and FIG. 10, a broken line rectangular frame defines the boundary of an enlarged view and form no part of the claimed design.
